UNITED STATES PATENT OFFICE.

CHARLES W. TAYLOR, OF SALT LAKE CITY, UTAH.

CARBURETOR.

Application filed September 3, 1924. Serial No. 735,554.

This invention relates to fuel feed devices for internal combustion engines and particularly to a carburetor especially adapted for use in fuel feed systems where 5 the fuel is heated preliminary to its entering the cylinder or combustion chamber.

One object of the present invention is to provide suction actuated valves for the air and fuel supply ducts, the two valves 10 being arranged in such wise that the fuel valve is normally held to its seat by the nozzle but will be released and permitted to open as the air valve is moved to its open position.

15 A further object is to simplify the construction of the carburetor whereby several advantages are secured, amongst which are the following: The carburetor works with a vacuum feed although the vacuum tank at 20 present in general use is dispensed with; no float chamber or float is necessary in the present construction; in addition to the carburetor casing there are practically but five parts, all of which are supported or carried 25 on the base of the carburetor casing and as the base portion of the casing is a separable section all of said parts can be easily removed from the casing by simply detaching the base section.

30 With these and other objects in view, the invention consists in certain details of construction and combinations and arrangements of parts, all as will be hereinafter more fully described and the novel features 35 thereof particularly pointed out in the appended claims.

In the accompanying drawings,—

40 Figure 1 is a view showing more or less diagrammatically a fuel feed system embodying the present invention;

Fig. 2 is a longitudinal sectional view of the carburetor removed from the system;

45 Fig. 3 is a transverse sectional view taken on the line 3—3 of Fig. 2. Fig. 4 is a bottom plan view of the carburetor;

Fig. 5 is a detail view of the element for preheating the liquid fuel; and,

Fig. 6 is a similar view of a modified form of heating unit.

50 It is believed that practically all brands of present-day gasoline contain at least a small percentage of water whose presence reduces the efficiency of internal combustion engines and for this reason, the present in-

vention contemplates the provision of a carburetor for fuel feed systems wherein the fuel, usually gasoline, is heated before it reaches the carburetor. It is believed that this preheating of the gasoline tends to vaporize the particles of water that might 55 otherwise pass to the combustion chamber in the form of a liquid but to insure this vaporization of the fuel as well as to thoroughly commingle the fuel with air, the present carburetor seeks to discharge the heated fuel 60 into a mixing chamber from a nozzle located centrally of said chamber and entirely surrounded by a film of air, so to speak, 65 passing said nozzle on its way to the combustion chamber. For these reasons the 70 present invention is especially applicable to carburetors in systems where the liquid fuel is preheated.

As illustrated in Fig. 1 of the drawings 75 the liquid fuel is brought from a suitable source by a supply pipe 10 to a heating unit 11 which, as illustrated in Figs. 5 and 6, may comprise either a seamless tube 12 located within the exhaust manifold 14 or a jacket 13 formed on the exterior of said 80 manifold. In each instance, the fuel entering the heating unit preferably passes through a jet 15 for the purpose of atomizing the fuel and thereby augmenting the heating thereof. From said heating unit 85 the fuel passes through a conduit 25 to the carburetor where it is thoroughly commingled with the proper proportion of air in a mixing chamber, after which it passes on to the usual intake manifold and thence 90 to the several cylinders, the flow of the combustible mixture being controlled by the manually operable butterfly valve 17.

To insure thorough commingling of the heated fuel with the air supplied to the 95 mixing chamber 22 of the carburetor, the internal construction of said carburetor is designed to cause the entering air to pass into the mixing chamber in a more or less circular film and the fuel is discharged into the chamber from a point within the circular film and in a direction substantially transversely of the direction of movement 100 of the air. This is accomplished by a novel arrangement of parts that not only secure a thorough mixture of the gasoline and air but which is simple and easily assembled in 105 or removed from the carburetor.

In the preferred embodiment of the invention illustrated in the drawings the carburetor casing is cylindrical and has a removable base section 18 in the side of which there are one or more air inlet openings 19 and in the bottom of which there is a gasoline inlet opening 20. The conduit 25 leads to said opening 20 and within the casing 10 there is a tubular stem 21 carried by base section 18 through which the gasoline passes to the mixing chamber 22, said mixing chamber being separated from the air inlets 19 by a valve 23. Said valve 23 is of substantially circular form, the inner wall base section 18 constituting a valve seat for the periphery of the valve and for reasons which will presently appear said valve comprises a sleeve portion 24 by means of which the valve is slidably carried on stem 21.

Within the mixing chamber, the stem 21 is provided with a nozzle 26 having a series of discharge ducts therein, these ducts being disposed substantially transversely of the mixing chamber whereby the fuel will be discharged directly into the more or less circular film of air that will pass up around the periphery of the valve 23 when said valve is raised above its seat.

The flow of fuel from stem 21 to nozzle 26 is governed by a check preferably in the form of a ball 27 which seats in the upper end of said stem and which is housed in the interior of nozzle 26. Said check valve will, of course, be held to its seat by gravity and the weight of nozzle 26 and to relieve it of the weight of said nozzle the latter is connected to the air valve 23, as by the spring 28 surrounding the stem and lower portion 40 of the nozzle, said nozzle preferably having a lower stem portion and an upper conical portion in which is located the fuel openings and which constitutes a flange or head against which said spring abuts. With this arrangement the suction created by the engine will raise the air valve 23 upward in the casing, said valve, through spring 28 raising the nozzle with the result that the vacuum in the carburetor will cause ball 27 to rise off its seat and permit fuel to flow through the nozzle. As soon as the motor is stopped, ball 27 and nozzle 26 will return to their original positions and close stem 21 and as the closure is air tight any fuel that has at that moment been sucked up into stem 21 will be retained due to the fact that no pressure can be exerted through the upper end of the stem, all as will be readily understood. This retention of fuel in the end of stem 21 provides for the immediate delivery of fuel to the engine when the latter is again started and eliminates the use of a vacuum tank or float chamber.

To permit a substantially unadulterated fuel to be fed to the motor when starting

up, the seat for valve 23 constituted by the wall of base section 18 is of sufficient length to allow the upward movement of valve 23 to elevate nozzle 26 and thereby release valve 27 before said valve 23 passes the shoulder 70 on the base to allow air to enter. This causes a rich mixture to be fed to the motor initially but after the motor has been started and the suction in the carburetor increased, valve 23 will be raised above said shoulder 75 and air admitted in proper proportions. In actual practice, satisfactory results have been obtained with a structure wherein the valve 27 was free to open after valve 23 had moved one-sixteenth of an inch and valve 23 80 was simultaneously opened by a further movement of three-sixteenths of an inch. Any movement of valve 23 over a quarter of an inch would then have no effect on the nozzle but would function to admit more 85 air and, due to the increased suction, a larger amount of fuel would be drawn into the carburetor. This arrangement of having the air valve open the fuel control valve in advance of air being admitted eliminates the 90 necessity of utilizing a manually controlled choke valve in many instances. As a manually controlled choke valve may be desired under some circumstances, as in unusually low temperatures, the admission of air 95 through the inlets 19 can be regulated by a valve 30 having openings 39 therein, said valve preferably being rotatable on base section 18 to move the openings 39 relatively to inlets 19 to vary the size of said inlets. 100 Valve 30 can be operated from the dash by a connection 31 and movement of said valve is limited by a projection, such as depending pin 32 working in a slot 33 in a flange at the bottom of base section 18.

To limit the movement of nozzle 26, the conical head thereof is adapted to engage an adjustable stop, preferably in the form of a conical ended screw plug 34 projecting through the side of the carburetor above said nozzle. While movement of the nozzle is thus limited by a fixed stop, the connection formed by spring 28, between the nozzle and valve 23 being resilient, the opening movements of said valve is dependent upon the 115 degree of acceleration of the motor. With a feed system embodying a fuel preheating means and a carburetor such as shown and described, a higher degree of efficiency is obtained due to the fact that the preheated fuel carries its water content in the form of a vapor and the entire body of fuel is thoroughly commingled with the air. The heated admixture, furthermore, being heated is more or less vaporized, as distinguished 120 from being atomized and remaining in liquid form, and is more or less expanded, thus securing a greater compression and insuring thorough and complete combustion of the entire mixture. This not only results 130

in obtaining greater power but it also decreases the formation and accumulation of carbon deposits in the cylinders.

What I claim is:

5. 1. In a carburetor, the combination of a casing having an air inlet near its base and a mixing chamber above said inlet, a nozzle in said chamber through which fuel is discharged into said chamber, a fuel passage 70 leading to said nozzle, a valve in said fuel passage, said nozzle being free to move relatively to said valve to release the other, and a suction operated valve controlling the passage of air from said inlet to said chamber, 75 said fuel valve being adapted to be opened in advance of the air valve and the opening of the fuel valve being dependent upon the movement of the air valve to actuate the nozzle and release said fuel valve. 80
2. In a carburetor, the combination of a casing having a mixing chamber and air inlets therein, a fuel supply duct, a suction operated valve for said duct, a nozzle holding said valve to its seat and through which 85 the fuel is discharged into the chamber, a suction operated valve controlling the passage of air from said air inlets to said chamber, and connections between said air valve and nozzle said air valve and nozzle being movable with respect to the fuel valve 90 during initial opening movement of the air valve to move the nozzle to release the fuel control valve. 95
3. In a carburetor, the combination of a casing having a mixing chamber and air inlets therein, a fuel supply duct, a suction operated valve for said duct, a nozzle holding said valve to its seat and through which 100 the fuel is discharged into the chamber, a suction operated valve controlling the passage of air from said air inlets to said chamber, resilient connections between said air valve and nozzle whereby an opening movement of said air valve will move the nozzle to release the fuel valve, said air valve and fuel valve being disconnected and means for limiting the movement of said nozzle. 105
4. In a carburetor, the combination of a casing having an air inlet near its base and a mixing chamber therein above said inlet, a stem having a fuel supply passage therein, said stem projecting into the mixing chamber, a nozzle on said stem, a valve for the 110 fuel supply passage within said nozzle and an air control valve on said stem, said nozzle being slidable on the stem and movable relatively to the fuel valve to release said fuel valve. 115
5. In a carburetor, the combination of a casing having an air inlet near its base and a mixing chamber above said inlet, a tubular stem on the base extending into the chamber and through which fuel is supplied 120 to the chamber, a nozzle loose on said stem, and separately movable suction operated valves on said stem controlling the passage of air and fuel to said mixing chamber, said nozzle being movable relatively to said fuel valve to permit the latter to be opened. 125
6. In a carburetor, the combination of a casing having an air inlet near its base and a mixing chamber above said inlet, a tubular stem on the base extending into the chamber and through which fuel is supplied 75 to the chamber, a suction operated valve for said fuel supply, a nozzle on the stem and holding said valve to its seat, said nozzle being loose on said stem and movable with respect to the fuel valve to permit the latter 80 to be opened, a valve controlling the passage of air from said inlet to the mixing chamber, and connections between the air valve and nozzle to release the fuel valve when the air valve is opened. 85
7. In a carburetor, the combination of a casing having an air inlet and a mixing chamber therein, a fuel supply duct, a check valve for said duct, a nozzle for said duct holding said check valve to its seat, a suction operated valve controlling the passage of air from said inlet to the mixing chamber, and connections between said air valve and nozzle for moving said nozzle relatively 90 to said fuel valve to release the latter as the air valve is moved to its open position, said air valve having a comparatively long seat whereby admission of air to the chamber is delayed until after the fuel valve is opened. 95
8. In a carburetor, the combination of a casing having an air inlet and a mixing chamber therein, a fuel supply duct, a check valve for said duct, a nozzle for said duct holding said check valve to its seat, a suction operated valve controlling the passage of air from said inlet to the mixing chamber, connections between said air valve and nozzle for moving the nozzle relatively to 100 said fuel valve to release the latter as the air valve is moved to its open position, said fuel valve being released in advance of the actual opening of the air valve. 105
9. In a carburetor, a casing having an air inlet and a mixing chamber therein, a check valve between said air inlet and chamber 115 controlling the passage of air to the chamber, a stem projecting into the chamber and having a fuel passage therein, a check valve for said fuel passage a nozzle slidable on said stem and holding said fuel valve to its seat, and a resilient connection between said air valve and nozzle to move said nozzle with respect to the fuel valve to release said fuel valve as the air valve is moved to permit air to flow to the mixing chamber. 120
10. In a carburetor, the combination of a casing having an air inlet near its base and a cylindrical mixing chamber above said inlet, a stem on said base centrally disposed in said chamber and having a fuel passage 130

therein, a check valve in said stem, a nozzle loose on the stem adapted to releasably hold said check valve seated, said nozzle having a plurality of fuel passages therein, and an air valve controlling the passage of air from the inlet to the mixing chamber, said air valve being substantially circular and ex-

tending beyond the side edges of the nozzle and the passages in said nozzle being radially disposed whereby the fuel will be discharged from the nozzle into contact with a surrounding film of passing air. ¹⁰

CHARLES W. TAYLOR.
